Inventor:

Anders David Berglind
By: B. Amiger, Atty.

UNITED STATES PATENT OFFICE.

ANDERS DAVID BERGLIND, OF KLOSTERPOSSEN, SKIEN, NORWAY.

APPARATUS FOR BLEACHING CELLULOSE AND LIKE SUBSTANCES.

1,329,824.

Specification of Letters Patent.

Patented Feb. 3, 1920.

Application filed May 8, 1918. Serial No. 232,423.

To all whom it may concern:

Be it known that I, ANDERS DAVID BERGLIND, a subject of the King of Sweden, residing at Klosterpossen, Skien, Norway, 5 have invented an Improvement in Apparatus for Bleaching Cellulose and like Substances, of which the following description, in connection with the accompanying drawings, is a specification, like characters on 10 the drawings representing like parts.

In the bleaching of cellulose and like substances with chlorin, the mass is generally treated in open vats, where the air has free access and in which steam is employed to 15 produce the desired whiteness. That hereby much chlorin is wasted and the consumption of steam is great will easily be understood.

It has been tried to perform the bleaching in closed vessels, but this method has not given the desired result, as at a certain point of the process air and water have to come into action in order to obtain the desired whiteness of the mass.

25 The present invention has for its object an apparatus for bleaching, washing and airing of the mass in a most economical manner.

According to my process the treatment 30 with chlorin is carried out in a closed vessel, and then the mass is subjected to a repeated alternate washing and airing.

The apparatus employed is illustrated on the appended drawing, where Figure 1 represents the apparatus viewed from one end 35 showing a cross section of the washing and airing devices, and Fig. 2 is a side view of the apparatus showing a longitudinal section of the said devices.

40 A is the ordinary rotating closed vessel in which the mass is treated with bleaching liquid, said vessel having charging and discharging openings, which are closed by covers *a, a'*.

1 is the vat in which the washing of the mass takes place, the said vat resting in a suitable packing material. The one side (or both) of the vat is provided with a lining 2 of filtering stone through which the 45 wash-water is filtered, a chamber 3 being provided behind said lining for collecting said water. The chamber 3 has a drain 4 with valve 5 for stopping the flow. By the arrangement of the filter stone lining 2 the 50 waste of fibers is obviated. In the vat 1 is

a stirrer 6 on a shaft 6^a, which extends outside the vat and has a cog-wheel 6^b for power transmission from a motor or otherwise. 7 is a pipe extending along the top of the vat and provided with perforations 60 for sprinkling water into the vat. In order to increase the action of the stirrer 6 the cross section of the bottom of the vat is semicircular corresponding to the circumference of the stirrer 6. The bottom of the 65 vat is inclined toward one end where an outlet 8 is provided. A slide 21 is provided for shutting off said outlet. From the outlet 8 a pipe 9 leads to a centrifugal pump 10, and from the latter a pipe 11 leads to 70 the place where the product is to be used. The pipe 11 is provided with a cut-off valve 12 below which is located a branch leading to the airing device, the flow through which is controlled by the valve 13.

75 The airing device consists of a hood-shaped casing 14, which is affixed to a base 14^a resting on the edge of the vat 1. The casing is provided at the back with an aperture for communication with the branch 80 13, while at the front it opens direct into the vat 1 at 15. The casing 14 is provided inside with an inclined plate 16, located beneath said aperture for the purpose of spreading the mass entering through the 85 branch 13. Underneath the plate 16 is a tube 17 which is provided with apertures 18, said tube being at 19 connected to a fan-blower 20.

The working of the apparatus is as follows:

The mass is treated in the cylinder A for about five hours, and is then discharged into the vat 1. The stirrer 6 is now rotated and water is introduced through pipe 7. 95 During this treatment the outlet 8 is closed. After the lapse of a suitable time the valve 21 is opened, the pump 10 is started, the valve 12 is closed and the valve 13 is now opened. The mass is now drawn through 100 pipe 9 to pump 10, and thence up through the standpipe 11, passes into the branch 13, and thence into the casing 14, where it is distributed on the plate 16, and on dropping from the edge of the latter the mass is 105 penetrated by currents of air from the apertures 18 and drops then into the vat 1, where it is subjected to a renewed washing operation.

110 This alternate washing and airing of the

mass is carried on until the mass after about two hours treatment is quite white and free from lye and gases.

When the washing and airing operations 5 are finished, the valve 13 is shut off and the valve 12 is opened so that the mass may be forwarded to the place where it is to be used.

What I claim as my invention is:—

- 10 1. In apparatus for bleaching cellulose, a bleaching vessel, a vat to receive bleached material, stirring means in the vat, means for sprinkling water into the vat, a pump, a valved connection between the pump and the bottom of the vat, a discharge pipe leading from the pump, and arranged to discharge material drawn from the vat by the pump back into the vat, and means to force air through said material as the same is discharged by the pump into the vat.
- 15 2. Apparatus for bleaching cellulose,

comprising a vat, stirring means in the vat, means to draw material from the bottom of the vat and to discharge the same at an elevated point back into the vat, and means to 25 force air through such material as the same is discharged back into the vat.

3. In apparatus for bleaching cellulose, a vat, stirring means in the vat, a spreading plate arranged above the vat, means to 30 withdraw material from the bottom of the vat and to discharge the same onto said spreading plate so that such material falls from the spreading plate back into the vat, and means to force air through such material 35 as the same falls back into the vat.

In testimony whereof I have signed my name to this specification.

ANDERS DAVID BERGLIND.
